SLIDER FOR SLIDING FASTENERS

Erich Engel, Tonteg, near Pontypridd, England,
assignor to Aero Zipp Fasteners Limited, London, England, a British company

Application April 13, 1943, Serial No. 482,835
In Great Britain January 25, 1943

14 Claims. (Cl. 24—205.15)

1

The present invention relates to sliders for sliding fasteners and more particularly to sliders for zip fasteners.

In many cases objectionable wear is likely to occur on a slider in ordinary use. For example, when a metallic slider made by casting is employed in a covered zip fastener of the known type in which the fastening members are covered by strips of a fabric to improve the appearance of the fastener, it has been observed that the covering strips soon become soiled owing to the fact that the metal of which the cast slider is made is too soft to withstand the abrasive action of the covering strips on the adjacent inner surface of the slider when the slider is operated. An objectionable wear is also likely to occur, when a slider made of artificial resinous, cellulosic, or similar plastic material is used, particularly in connection with a covered zip fastener. It is another object of the present invention to overcome these drawbacks.

It is another object of the invention to provide new means for attaching a pull member to the slider in such a way that the front plate of the slider may be made substantially flat.

It is a further object of the invention to provide simple means for covering the back of the slider by a fabric or the like material to prevent contact between the back of the slider and either an article lying beneath the slider or the body of the wearer of a garment to which the fastener is attached.

It is still another object of the invention to provide means for preventing the material of an article to which the fastener is attached or on which the fastener lies when in use from becoming caught between the interlocking fastening members. Other objects and advantages of the invention will become apparent from the subjoined detailed description taken in conjunction with the accompanying drawings, in which:

Fig. 1 is a general view of a zip fastener having a slider constructed in accordance with this invention;

Fig. 2 is a cross-section along the line II—II of Fig. 1;

Fig. 3 is a perspective exploded view of the front and rear wings and the intermediate plate of the slider of Fig. 1;

Fig. 4 is a perspective view of a modified plate;

Figs. 5 and 6 illustrate a vertical and horizontal sectional view respectively of the slider, shown in Fig. 1;

Fig. 7 is a perspective view of a slider in accordance with this invention without a yoke as

2

normally provided for attaching a pull member;

Fig. 8 is a perspective view of a modified construction of a slider without a yoke;

Fig. 9 shows the pull member of the slider of Fig. 8 in different positions;

Fig. 10 is a perspective view of a further modification of the slider;

Fig. 11 illustrates a still further modification of a slider without yoke;

Fig. 12 is a perspective exploded view of the slider shown in Fig. 11;

Fig. 12a shows in a perspective exploded manner the pull member and the intermediate insert plate separated from each other of the slider shown in Fig. 12;

Fig. 13 illustrates a sectional view of a slider having an insert protruding at either side of the adjacent wing beyond the wing and forming a loop outside the slider;

Fig. 14 illustrates a further modification of a slider according to the invention;

Fig. 15 is a perspective exploded view of the front and rear wings, the intermediate insert plate, and a second insert of the slider shown in Fig. 14;

Fig. 16 illustrates another slider, in which the insert is arranged adjacent the rear wing of the slider;

Fig. 17 is a perspective exploded view of the front and rear wings and the intermediate insert plate of the slider of Fig. 16.

Referring first to Figs. 1 to 3, the zip fastener is a common form of a covered fastener having two tapes 1 and 2 with fastening members 3 attached thereto in uniformly spaced relation. The fastening members 3 are covered by strips 4 and 5 of a fabric which are attached to the tapes 1 and 2 respectively in known manner. For interlocking and releasing the members 3, and thus

for closing and opening the fastener, a slider generally denoted by numeral 6 is provided having a yoke 7 for attaching a pull member 8 to actuate the slider. The slider 6 comprises a body of usual shape, having opposed parallel wings 12 and 13 connected at one end by a substantially triangularly shaped neck portion 14. The front wing 13 has inturned flanges 15, and the rear wing 12 has inturned flanges 17. To prevent wear between the front wing 13 and the

covering strips 4 and 5 a substantially Y-shaped insert or plate 16 of wear resisting material is provided so as to cover substantially the entire inner surface of the front wing 13 of the slider. Preferably, the plate 16 consists of wear resisting sheet metal. It may be loosely inserted into

50 55

the slider before the slider is attached to the fastener. When the slider is attached to the fastener, the plate 16 is held in position by the fastening members 3 and the covering strips 4 and 5 preventing it in co-operation with the flanges 15 from slipping sideways out of the slider, while the neck portion 14 prevents the plate from leaving the slider at its top, and the shape of the plate 16 and the flanges 15 of the wing 18 prevent the plate from leaving the slider at its bottom. If desired, the plate 16 may be slightly bent as shown in Fig. 4 at 23, 24 and 25 to anchor it more securely in the slider, and the plate 16 may be fixed to the front wing 18, for example by soldering along its edges 21, 22 and 23 (see Figs. 5 and 6).

According to other embodiments of the invention, as shown for example in Figs. 7-15 to be described hereinafter, the provision of the insert makes it possible to dispense with a yoke for attaching a pull member and to hold the pull member by means of the plate, whereby the manufacture of the slider, particularly when made of plastic material is simplified and the slider may be given a reduced overall thickness. In the use of sliding clasp fasteners, for example, in plackets of women's dresses and in men's trousers it has been found that the usual type of sliders with an upwardly projecting yoke causes difficulties in pressing the garments. The yoke will press into the garments and make the location of the slider apparent, even though it is concealed behind a flap.

According to the embodiment of a slider without a yoke as shown in Fig. 7, a front wing 30 and a rear wing 31 are connected in the usual way by or at a neck portion 32. The plate 33, which again may consist of wear resisting material, for example of sheet metal, is bent at its end adjacent the neck 32 so as to form lugs 34 and 35 to which a pull member 36 is hinged. The pull member 36 is given a shape so as to surround the front wing 30 of the slider laterally in its rest position. To operate the slider, the pull member 36 is gripped and raised to actuate the slider. The pull member 36 is provided with projections 37 adapted to engage, in its rest position, between adjacent fastening members of a non-covered zip fastener or to press on a covering tape of a covered zip fastener in order to lock the slider against unintentional movement. The pull member 36 may be made of sufficiently stiff flexible material such as wire or leather or the like. It may, of course, assume many other suitable shapes different from the specific shape illustrated.

The slider illustrated in Figs. 8 and 9 comprises a front wing 41 and a rear wing 40 connected by or at a neck portion 42 of the same construction as the neck portion 14 shown in Fig. 3. The front wing 41 is provided with two grooves 43, 44 which are covered by a plate 45, thus forming two conduits through which a wire, band, string, or the like flexible material 46 is threaded, which serves as a pull member. The wire or the like 46 is provided with beads 47, 48 or the like means for facilitating gripping the wire to operate the slider. To close the fastener, the bead 48 is gripped and pulled. On pulling, the wire or the like 46 first assumes a position 46' as indicated in Fig. 9 and then moves the slider in the direction of closing the fastener. To open the fastener, the bead 47 is pulled, whereupon the wire or the like 46 first assumes

the position 46'' and then moves the slider in the direction of opening the fastener.

In the slider illustrated in Fig. 10, the front wing 50 and the rear wing 51 are connected by or at a neck portion 53 of the same construction as the neck portion 14 shown in Fig. 3. A plate 56 is provided with upturned lugs 55, protruding through corresponding openings in the front wing 50, the pull member 58 being hinged to the lugs 55. While in this embodiment the front surface of the slider formed by the front wing 50, the lugs 55, and the pull member 58 is not completely flat, yet the overall thickness of the slider is considerably reduced in comparison with an ordinary slider having a yoke for attaching the pull member.

Still another embodiment of a slider without a yoke is illustrated in Figs. 11, 12 and 12a. In this embodiment the front wing 60 and the rear wing 61 are connected by a neck portion 62. A substantially Y-shaped plate 64 recessed at 70 and 70' lies adjacent the inner surface of the wing 60. The wing 60 is recessed at 65 and the plate is provided with a groove 66 for loosely receiving a transverse rod 167 of a pull member 67, said transverse rod 167 being held in the groove 66 by the covering strips of a zip fastener (for example covering strips 4 and 5 as shown in Fig. 1) when the slider has been threaded onto such a zip fastener. The pull member 67 has two projections 68 and 69, for pressing against the covering strips and the fastening members (for example covering strips 4 and 5 and fastening members 3 as shown in Fig. 1) of the zip fastener to lock the slider against unintentional movement when the pull member lies flat is illustrated in Fig. 11. To operate the slider the gripping means 68 attached to the pull member 67 is raised and pulled. Thereby the pull member 67 is first raised whereby the slider is released from its locked position and the slider is moved in accordance with the pull exerted on the slider.

The slider illustrated in Fig. 13 has an insert 15 preferably made of flexible material such as fabric, leather, or the like which protrudes beyond the adjacent wing 71 at either side. Outside the slider the insert is folded back to form a loop 78 serving as a pull member. The insert 15 is held in position by the neck portion of the slider which extends through a corresponding hole in the insert.

The slider illustrated in Figs. 14 and 15 is provided with an insert 80 of flexible material such as fabric, leather or the like which protrudes from the slider at either end. The insert is held in position by the neck portion 84 extending through a hole 85 in the insert 80. The insert has free ends 81 and 82 serving as pull members for closing and opening the fastener respectively. A second insert 83 formed by a Y-shaped metal plate is provided to prevent wear between the fastener and the first insert 80.

In the slider shown in Figs. 16 and 17 the insert 95 lying adjacent the rear wing 96 is made of sheet metal and protrudes beyond the upper end 97 of the rear wing 96, the protruding part 94 being slightly bent upwards towards the front. The part 94 serves to prevent any material to which the zip fastener is attached or on which it lies from being caught between the fastening members.

It should be understood that the drawings are given by way of example only and that many

modifications are possible without departing from the spirit of this invention.

I claim:

1. A slider for a sliding fastener comprising two wings, each with inturned flanges, connected at a neck portion, and at least one substantially Y-shaped insert arranged adjacent the inner surface of one of said wings so as to lie between the inner surface of said wing and the fastener when the slider is attached to the fastener.

2. A slider for a sliding fastener comprising two wings, each with inturned flanges, connected at a neck portion, and at least one substantially Y-shaped insert covering substantially the entire inner surface of one of said wings to prevent any contact between said surface and the fastener when the slider is attached to the fastener.

3. A slider for a sliding fastener comprising two wings connected at a neck portion, flanges on said wings, and at least one insert plate adapted to cover at least part of the inner surface of one of said wings, said insert plate being loosely inserted into the slider and so shaped as to be held immovably in position by said flanges and the fastener when the slider is attached thereto, to prevent any contact between said part of the inner wing surface and the fastener.

4. A slider for a sliding fastener comprising two wings, each with inturned flanges, connected at a neck portion, and a substantially Y-shaped insert plate shaped so as to cover at least a substantial portion of the inner surface of one of said wings, said insert plate being arranged adjacent the inner surface of one of said wings, the ends of said insert protruding beyond the edges of said wing, and said protruding ends of the insert being bent for abutting cooperation with the edges of said wing so as to be held in position by said edges of the wing when the slider attached to the fastener is displaced relative to the latter.

5. A slider for a sliding fastener comprising two wings connected at a neck portion, an insert made of a wear resisting material and arranged adjacent the inner surface of one of said wings, a yoke arranged on the outer surface of one of said wings, a pull member connected with said yoke, and flanges arranged on one of said wings and engaged with said insert so as to hold same in position when the slider attached to the fastener is displaced relative to the latter.

6. A slider for a sliding fastener comprising a front wing and a rear wing connected at a neck portion, an insert made of a wear resisting material and arranged adjacent the inner surface of said front wing, a yoke arranged on the outer surface of said front wing, a pull member connected with said yoke, and flanges arranged on said front wing and engaged with said insert so as to hold same in position when the slider attached to the fastener is displaced relative to the latter.

7. A slider for a sliding fastener comprising a front wing and a rear wing connected at a neck portion, a substantially Y-shaped insert plate arranged adjacent the inner surface of said rear wing, an end of said insert plate protruding beyond said rear wing in the region of the neck portion, said protruding end being slightly bent towards said front wing in order to substantially prevent foreign matter from being caught between the fastening members of the fastener when the slider is attached thereto, a yoke arranged on the outer surface of said front wing, a pull member connected with said yoke, and

flanges arranged on said rear wing and engaged with said insert plate so as to hold same in position when the slider attached to the fastener is displaced relative to the latter.

5 8. A slider for a sliding fastener comprising two wings, each with inturned flanges, connected at a neck portion, at least one substantially Y-shaped insert arranged adjacent the inner surface of one of said wings, and a pull member for actuating the slider, said pull member being attached to said slider by means of said insert.

10 9. A slider for a sliding fastener comprising two wings connected at a neck portion, at least one insert arranged adjacent the inner surface of one of said slider wings and protruding beyond said wing, the protruding end of said insert forming a pull member for actuating the slider.

15 10. A slider for a sliding fastener comprising two wings connected at a neck portion, at least one insert arranged adjacent the inner surface of one of said wings, a pull member for actuating the slider, and means provided on said insert for attaching said pull member.

20 11. A slider for a sliding fastener comprising two wings connected at a neck portion, at least one insert arranged adjacent the inner surface of one of said wings and protruding in the region of the neck portion beyond said wing, a pull member for actuating the slider, and means provided on the protruding part of said insert for pivotally connecting said pull member to said insert.

25 12. A slider for a sliding fastener comprising two wings connected at a neck portion, at least one insert arranged adjacent the inner surface of one of said wings, a pull member for actuating the slider, and means provided on the insert and protruding through a recess in said wing for pivotally connecting said pull member to said insert.

30 13. A slider as defined in claim 12, and wherein said recess is so shaped as to surround at least part of said pull member in its rest position.

35 14. A slider for a sliding fastener comprising two wings connected at a neck portion, and at least one insert covering substantially the entire inner surface of one of said wings to prevent substantially any contact between said surface and the fastener when the slider is attached to the fastener, said insert being made of flexible material, at least one end of said insert protruding beyond said wing to form a pull member.
